Des. 209,818

Patented Jan. 9, 1968

209,818

WINDOW GUARD

Albert Udin, 4234 Park Ave., Bronx, N.Y. 10457

Filed May 19, 1967, Ser. No. 7,196

Term of patent 14 years

(Cl. D13—1)

Fig.1

Fig.2

Fig.5

Fig.3

Fig.4

Fig.6

FIGURE 1 is a plan view of a window guard showing my new design;

I claim:

The ornamental design for a window guard, substantially as shown.
